UNITED STATES PATENT OFFICE.

HENRI GUILLOU, OF PARIS, FRANCE.

IGNITION DEVICE FOR EXPLOSION-ENGINES.

SPECIFICATION forming part of Letters Patent No. 741,329, dated October 13, 1903.

Application filed February 15, 1902. Serial No. 94,291. (No model.)

To all whom it may concern:

Be it known that I, HENRI GUILLOU, a citizen of the Republic of France, residing at Paris, France, have invented certain new and useful Improvements in or Relating to Ignition Devices for Explosion-Engines, (for which I have made application for Letters Patent in Great Britain under No. 501, dated January 7, 1902; in France under No. 312,803, dated July 18, 1901; in Germany, dated November 11, 1901; in Belgium under No. 127,863, dated January 9, 1902, and in Switzerland, dated January 11, 1902,) of which the following is a specification.

15 The present invention relates to an improved construction of incandescent-tube ignition device applicable for explosion engines or motors.

The construction comprises a clamping device and a thumb-screw which facilitate the securing in place and rapid removal of the ignition-tube for cleaning and repairing purposes and to enable it to be replaced at once without the aid of keys or tools, and also the arrangement of a clearance-chamber situated in the ignition-passage in order to regulate the exact time of ignition.

In the accompanying drawings, Figures 1 and 2 represent front and side vertical elevations of the device. Fig. 2^a is a sectional view of the parts seen in Fig. 3. Fig. 3 is a horizontal section on the line *x* *x* of Fig. 1. Fig. 4 shows the perforated ring which regulates the admission of the air to the chimney 2 of the ignition device. Fig. 5 is a perspective view showing the means of clamping the ignition device to the gas-supply tube. Fig. 6 is a vertical central section of the device as shown in Fig. 1 in a plane parallel to the plane of the paper.

Like numerals indicate like parts throughout the drawings.

According to this invention, the ignition-tube 1, of refractory material, is arranged transversely to and extending outward from the chimney 2 and is contained in a tube or protector 3, so as to be in contact with the flame of a Bunsen burner 4, arranged at the base of the chimney and secured in position by means of a nut or in any other manner. A perforated ring 5 regulates the admission to the burner of air which enters the chimney

so as to support combustion. A socket 6, provided with a mica window, is arranged on a level with the tube 1 in order to permit of the inspection of its state of incandescence. The Bunsen tube 4 is so curved as to allow of an intimate mixture of the air entering passages 7 therein with the gas passing through the tube. The interior of the incandescence tube 1 communicates with the explosion-chamber of the motor by a passage 8 in a block or tube 9, provided with a collar or union 10, by which the apparatus is secured to the motor. The other end of the passage 8 is closed by a screw-plug 11, which when removed allows the passage to be inspected and cleaned. The passage 8 also communicates or is provided with an explosion-chamber 30. This chamber is closed by a screw-plug 13, carrying a threaded rod 14, on which are secured a number of disks or rings 15. This set of disks or rings is adapted to fill more or less the interior of the explosion-chamber, so as to control in an absolutely precise manner the point or time of the ignition of the mixture by storing up a smaller or greater quantity of inert gas from the previous explosion, so as to cause the explosive mixture (driven back by the piston during compression-stroke) to reach earlier or later the incandescent portion of the ignition-tube 1. Thus the time of ignition is regulated by lessening or increasing the number of the disks 15.

In order to rapidly attach or detach the ignition-tube, it is provided with a seat or projection 16, which rests partly in a recess 17 in the ignition-tube casing and partly in a recess 18 in the block or tube 9, before referred to. An asbestos washer 19 is placed in the recess 17. The casing or block 20, which is integral with the chimney, is provided with two projecting lugs 21 22, each of which has a grooved or lipped end, the outer end of the tube or block 9 being placed between the lugs. These lugs are then engaged and gripped by a cap or yoke 23 with inwardly-turned arms 24, which engage in the grooves in the lugs, a thumb-screw 25 being provided to tighten the parts by turning the screw 25, whereby the lugs are clamped and strongly held thereby, tightly clamping the whole together.

What I claim as my invention, and desire to secure by Letters Patent, is—

1. In ignition devices for explosion-motors,
a device for securing the ignition-tube comprising a yoke or cap, lugs thereon, a screw in the yoke, a block having flanges and being
5 provided with an ignition-passage, and with
grooves extending up to the flanges, the said
yoke or cap being adapted to slide in the
grooves, the said flanges on the block limit-
ing the movement of the yoke and insuring
10 the correct position of the parts, substantially
as described.
2. An ignition device for explosion-motors,
comprising a tube secured to the motor, a
block having two projecting lugs embracing

15 said tube, a clamping-yoke engaging the lugs,
a tightening-screw in the yoke and bearing
against the tube and an ignition-tube having
a seat or projection resting partly in a recess
in the tube secured to the motor and partly
20 in a recess in the chimney.

In testimony whereof I have signed my
name to this specification in the presence of
two subscribing witnesses.

HENRI GUILLOU.
